FIG. 6.

UNITED STATES PATENT OFFICE.

JAMES P. MARSH, OF CHICAGO, ILLINOIS.

AIR-VALVE FOR STEAM-RADIATORS.

SPECIFICATION forming part of Letters Patent No. 317,818, dated May 12, 1885.

Application filed December 10, 1884. (No model.)

To all whom it may concern:

Be it known that I, JAMES P. MARSH, a citizen of the United States of America, residing at Chicago, in the county of Cook and 5 State of Illinois, have invented certain new and useful Improvements in Air-Valves or Steam-Traps, of which the following, in connection with the accompanying drawings, is a specification.

10 In the drawings, Figure 1 is a side view or elevation of an air-valve or steam-trap embodying my invention. Fig. 2 is a section in the plane of the line $x x$ of Fig. 1, viewed in the direction indicated by the arrow there 15 shown. Fig. 3 is a section in the plane of the line $x' x'$ of Fig. 1, viewed in the direction indicated by the arrow shown at that line. Fig. 4 is a detail, the same being a side view of the valve and reamer. Fig. 5 is a like representation of the spring wire or rod connecting the head-piece or top plate to the base-piece. Fig. 6 is a detail, being a top view of 20 the valve-plate and its cylinder; and Fig. 7 is a detail, being a side view of the lower part of 25 the steam-tube.

Like letters of reference indicate like parts.

My invention relates to that class of air-valves or steam-traps commonly employed in connection with steam-heaters, and which are 30 operative owing to the contraction and expansion of some of their parts.

My invention has for its object the further improvement of valves or traps of that class, in the respects hereinafter more fully set forth.

35 A represents the bottom piece or base of the valve or trap. This piece is tapped to admit of its being suitably connected to the steam coil or heater B, by means, for example, of a short pipe or tube, a , externally screw-threaded, and a' is a channel or conduit communicating with the said tube. A hole or 40 opening, b , is also made in the base. In the upper face of the base-piece is a socket, c , and d is a tubular piece or evaporating-cup fitted 45 upon the piece A and extending above it, as shown.

B' is a drip-tube entering the opening b , and C is a screw-coupler run upon the lower end of the said tube, and also upon the main portion e of the drip-pipe. This coupler has in-

ternal screw-threads, and the meeting ends of the parts coupled by it are correspondingly screw-threaded. By these means I am enabled to couple the parts together firmly and with facility.

55

C' is a U-shaped wire or rod made waving, as indicated at f , and also having the quality of being yielding, flexible, or spring-like. The bow or bow-shaped end of this wire I set into the socket c , and secure it there in the manner hereinafter described. The upper ends of the wire C' , I flatten, as shown at g .

D is a flattened tube notched at its lower end, as indicated at h , to set down neatly over the bowed end of the wire C' , after the latter 60 has been arranged in the socket c . The lower end of this tube rests on the bottom of the said socket and incloses or encircles the opening a' . After the said wire and tube have been so arranged, I secure them in place by means of 65 solder i , (preferably hard solder,) poured into the said socket.

E is the valve-plate, which is rigidly secured to the upper end of the tube D , and E' is the valve-opening. The upper ends or portions 70 of the wire C' pass freely through the plate E .

F is the head-piece or top plate. I secure this plate rigidly to the wire C' by passing the flattened parts $g g$ through correspondingly-formed holes in the said plate, and by turning 80 the said flattened parts down firmly upon the upper face of the said plate and solder them thereto.

G is a screw, or adjustable valve opener and closer, passing through the plate F and having its point adapted and arranged for closing and opening the opening E' . Extending downward from the screw or valve and rigidly attached thereto, or made in one part or piece therewith, is a reamer, G' , passing down 90 through but not filling the valve-opening.

H is a cylinder on the plate E . Openings j exist between the plate E and its cylinder. I is a removable cap fitted upon the upper end of the said cylinder. The cylinder H , as will 95 be perceived, is smaller in diameter than the cup d .

Some of the advantages resulting from the features of construction now described are as follows: By making the wire c' U-shaped and 100

in one piece, it may be applied with facility to the parts to be connected thereto, and is less liable to be pulled from its fastenings; also, the solder applied to its **U**-shaped end connects or cements it to the base-plate, and to the steam-tube with great firmness or rigidity. By making the evaporating-cup larger in diameter than the cylinder **H**, and arranging it directly under the said cylinder, the condensed steam or water which escapes or passes out through the valve, and which runs down on the inside of the said cylinder will drop into the said cup, where it will readily evaporate as the cup may be left open to aid evaporation. That which runs down on the tube **D** and wire **C'** will also run into the cup **d**. An outer tube or case may be dispensed with. I deem this cup especially advantageous in cases where it may not be convenient to employ a drip-pipe. By taking the unevaporated drip or drain directly from the lower end of the device, as by extending the tube **B'** directly into the bottom of the evaporating-cup, I facilitate construction, and also locate the drip-tube where it will not be as liable to injury and accidents as if more prominent or exposed. I also take the drip from a point at the base of the said cup **d**, and from the inside thereof. It frequently occurs that the valve-opening becomes clogged and requires cleaning. By providing the valve-screw with a reamer, in the manner shown and described, I am able to clean the valve-opening or to keep it open and unobstructed by occasionally turning the said screw back and forth sufficiently for that purpose. The escaping steam will blow out the dirt or particles so loosened. The valve is operated by the contraction and expansion of the steam-tube under different degrees of heat, and has a yielding connection through the instrumentality of the wire **C'**, with the base plate. The said wire is also contractable and expansible, but in different degree from the said tube.

45 In a pending application for Letters Patent for improvements in air-valves or steam-traps

filed by me April 14, 1884, Serial No. 127,758, I have shown and described two waving wires or springs connecting the top plate and the base-piece. I have also shown therein a flattened steam-tube, as well as some minor features of construction which are not herein shown and described. I do not, therefore, here intend to claim, broadly, any features of construction which may be made the subject-matter of claims in the said pending application; but,

Having thus described my invention, what I claim as new, and desire to secure by Letters Patent, is—

1. The combination, in an air-valve or steam-trap, of the **U**-shaped wire **C'**, all made in one piece, and having waving or bent portions **f**, a plate attached to the ends of the said wire and carrying a valve opening and closing device, and the base-plate, also connected to the said wire, substantially as and for the purposes specified.

2. The combination, in an air-valve or steam-trap, of the evaporator-cup **d**, and the cylinder **H**, the latter being arranged directly above, and having a smaller diameter than the said cup, substantially as and for the purposes specified.

3. The combination, in a steam-trap or air-valve, of a rotary and adjustable valve opener and closer, the reamer **G'**, depending from the said opener and closer, the valve-plate **E**, having therein the valve-opening **E'**, and the head-piece or top plate, **F**, carrying the said valve opener and closer, the said valve-plate and head-piece being attached, respectively, to metallic parts having unequal contraction and expansion under the influence of heat, substantially as and for the purposes specified.

In testimony that I claim the foregoing as my own I have hereto affixed my signature in presence of two witnesses.

JAMES P. MARSH.
